UNITED STATES PATENT OFFICE.

JAMES H. RAND, OF NORTH TONAWANDA, NEW YORK.

INDEX-CARD.

1,227,827.

Specification of Letters Patent. Patented May 29, 1917.

Application filed June 21, 1916. Serial No. 104,915.

To all whom it may concern:

Be it known that I, JAMES H. RAND, a citizen of the United States, and resident of North Tonawanda, in the county of 5 Niagara and State of New York, have invented new and useful Improvements in Index-Cards, of which the following is a specification.

This invention relates to a card index 10 system of the so-called overlapping card, visible index type, and consists in the novel features of construction hereinafter described and particularly pointed out in the claims.

15 In the accompanying drawings, which illustrate certain embodiments of the invention,—

Figure 1 is a face view showing a part of the index containing the invention; 20 Fig. 2 is a vertical section on an enlarged scale through one of the cards and the transparent sheath on its free margin;

Fig. 3 is a section similar to Fig. 2 showing a modification of the means for attaching the sheath to the card;

Fig. 4 is a longitudinal section illustrating diagrammatically the relation of the hinged cards and sheaths when the cards are lifted for the purpose of inspecting or writing upon an underlying card;

Fig. 5 is a face view of a part of an index containing a modification of the invention and showing adjustable indicators or signals attached thereto; and

35 Fig. 6 is a longitudinal section on an enlarged scale of the card, sheath and signal shown in Fig. 5.

A represents a frame of usual construction having an inwardly bent flange *a* at 40 each side forming a pair of inwardly facing guide channels. A series of bars or card carriers *B* are held with their ends in said guide channels, and to each card carrier *B* is hinged a card *C*. Said card carriers *B* 45 constitute means for supporting the cards in overlapping spaced relation with their free margins projecting one beyond another. Any desired form of card supports *B* may be used in place of the bars *B* shown, and 50 the parts thus far described may be of usual construction.

At the free margin of each card *C* there is attached a transparent sheath *D*, the widths of the several sheaths corresponding substantially to the widths of the spacing between the several cards effected by the ends

of the card carriers *B* which engage the guide channels. Said sheaths *D* thus lie side by side in substantially the same plane without overlapping, thereby avoiding undue thickness or bulkiness of the index, while at the same time they occupy and protect practically the whole exposed surface of the several overlapping cards excepting the uppermost card. The sheaths *D* are made of transparent resilient material such as sheet celluloid and comprise each a relatively long and narrow closed front face, which overlies the front side of the free margin of the cards, and rearwardly and 70 inwardly bent lips *d* and *d'*, one overlapping the other. The rear lip *d* may be cemented or otherwise permanently secured to the free margin of the card *C*, which extends 75 into the pocket in the sheath, as shown in Fig. 2; or, the free margin of the card *C* may be folded over as shown at *c* (Fig. 3), and the sheath may be attached to the card by inserting said folded over margin *c* endwise into the compartment formed between the face of the sheath *D* and the rearwardly and inwardly turned lip *d'*. Said lip *d'*, bent into the trough of the sheath, forms with the front face of the sheath *D* a compartment in which may be inserted an index 80 slip *E*, and preferably extends near enough to the bottom of the trough of the sheath to form such compartment wholly separate and partitioned off from the pocket formed 85 between the lip *d'* and the front face of the card *C* which extends into the pocket. The front face of the sheath *D* is preferably inclined from the lower or outer edge toward the face of the card thereby facilitating the movement or slipping of the edge of the next overlying card over the face of the sheath of the next underlying card when the cards are swung away from the frame as 90 shown in Fig. 4. The pocket formed behind the front compartment, between the lip *d'* and the lip *d*, is adapted to receive a card or paper insert *F* which is removably supported on the card *C* by said pocket. The front wall of said pocket is yieldingly urged 95 toward the rear wall by the resilience of the material of the sheath so as to form a spring clip which will grip the insert in the pocket and hold it frictionally in place against accidental dislodgment.

The index slips *E* may extend the whole 100 length of the sheaths as shown in Fig. 5, filling substantially the whole space within

the forward compartments of the sheaths, but preferably said index slips are shorter than said compartments so as to expose to view through the transparent sheaths the interior of the pockets at one or both ends 5 of the index slips, and preferably the inserts F and the cards C are visually differentiated so that when an insert F is removed or is missing from its proper pocket, its absence will be visually indicated by exposing 10 to view the visually differentiated margin of the corresponding card C. This may be accomplished, for example, by making the inserts F and the index slips E of white paper 15 or cardboard and the supporting cards C of colored paper, so that when any card F is removed from the series it will expose the different colored supporting card C to view through the transparent sheath, thus furnishing a signal that that insert is missing, 20 as illustrated in Fig. 1 on the card C indexed under the name "Jones".

The index illustrated in Fig. 5 is substantially the same as that shown in Figs. 1 and 25 2 save that the index slips E occupy the whole space within the index compartment of the sheath. In Figs. 5 and 6 an adjustable indicator member is shown having a signal portion g located in the front compartment 30 between the front face of the sheath and the index slip E, and a tab portion bent around the lower edge of the index slip and the edge of the lip d', and thence projecting outside of the sheath between the resilient 35 lips and lying substantially flatwise of the card. The indicator may be shifted lengthwise of the sheath by means of the projecting tab portion g'. The signal portion g of the indicator may be provided 40 with an aperture g², or other means serving as a pointer to indicate a letter or other inscription on the index slip E, as by exposing it to view through the aperture g². Letters A, B, C, etc., indicating grade of credit, 45 numerals indicating dates, or any other desired inscriptions may be applied to the index slips E, and attention may be visually directed to the desired inscription by means of the adjustable indicator.

50 It will be understood that the indication might be applied to the cards shown in Figs. 1 to 3 in the same manner as illustrated in Figs. 5 and 6.

I claim:

55 1. An index comprising a frame having inwardly facing guide channels, a series of cards, means engaging said guide channels for supporting said cards in overlapped spaced relation with their free margins projecting one beyond another, and a series of transparent sheaths on the front side of the free margins of the cards, the width of said sheaths corresponding substantially to the width of the spacing between the several 60 cards, whereby said sheaths may lie side by

side in substantially the same plane without overlapping.

2. An index comprising a frame having inwardly facing guide channels, a series of cards, means engaging said guide channels for supporting said cards in overlapped spaced relation with their free margins projecting one beyond another, and a series of transparent sheaths on the front side of the free margins of the cards, the width of said 70 sheaths corresponding substantially to the width of the spacing between the several cards, whereby said sheaths may lie side by side in substantially the same plane without overlapping, the faces of said sheaths being 75 inclined from the outer edge toward the face of the card to facilitate the edge of each overlying card slipping over the face of the sheath on the next underlying card when the cards are swung away from the frame. 80 85

3. An index comprising a frame having inwardly facing guide channels, a series of cards, means engaging said guide channels for supporting said cards in overlapped spaced relation with their free margins projecting one beyond another, and a series of transparent sheaths on the free edges of the cards, each sheath comprising a front compartment adapted to receive an index slip and a pocket behind said front compartment 90 95 adapted to receive a card insert.

4. An index comprising a frame having inwardly facing guide channels, a series of cards, means engaging said guide channels for supporting said cards in overlapped spaced relation with their free margins projecting one beyond another, and a series of transparent sheaths on the free edges of the cards, each having a closed front face and rearwardly and inwardly bent lips one overlapping the other, the front lip forming with the closed front face a compartment adapted to receive an index slip and forming with the rear lip a pocket adapted to receive a card insert. 100 105

110 5. An index comprising a frame having inwardly facing guide channels, a series of cards, means engaging said guide channels for supporting said cards in overlapped spaced relation with their free margins projecting one beyond another, and a series of transparent sheaths on the free edges of the cards, each sheath comprising a front compartment adapted to receive an index slip and a pocket behind said front compartment 115 120 adapted to receive a card insert, and index slips in said compartments shorter than said compartments, whereby the interior of said pockets will be exposed to view through said transparent compartments at one or 125 both ends of the index slips.

6. An index comprising a frame having inwardly facing guide channels, a series of cards, means engaging said guide channels for supporting said cards in overlapped 130

spaced relation with their free margins projecting one beyond another, and a series of transparent sheaths on the free edges of the cards, each sheath comprising a front compartment adapted to receive an index slip and a pocket behind said front compartment adapted to receive a card insert, index slips in said compartments shorter than said compartments to expose to view the interior of 5 said pockets through said transparent compartments at one or both ends of the index slips, and card inserts visually differentiated from said overlapped cards, removably held in said pockets, whereby the absence of any 10 card insert in the series from its pocket will be visually indicated by exposing to view the margin of the corresponding overlapped card in said pocket.

7. An index comprising a frame having 20 inwardly facing guide channels, a series of cards, means engaging said guide channels for supporting said cards in overlapped spaced relation with their free margins projecting one beyond another, and a series of 25 transparent sheaths on the free edges of the cards, each having a closed front face and rearwardly and inwardly bent lips one overlapping the other, the front lip forming with the closed front face a compartment 30 adapted to receive an index slip and forming with the rear lip a pocket adapted to receive a card insert, and index slips in said compartments shorter than said compartments, whereby the interior of said pockets 35 will be exposed to view through said transparent compartments at one or both ends of the index slips.

8. An index comprising a frame having inwardly facing guide channels, a series of 40 cards, means engaging said guide channels for supporting said cards in overlapped spaced relation with their free margins projecting one beyond another, and a series of transparent sheaths on the free edges of the 45 cards, each having a closed front face and rearwardly and inwardly bent lips one overlapping the other, the front lip forming with the closed front face a compartment adapted to receive an index slip and forming with 50 the rear lip a pocket adapted to receive a card insert, index slips in said compartments shorter than said compartments to expose to view the interior of said pockets through said transparent compartments at one or 55 both ends of the index slips, and card inserts visually differentiated from said overlapped cards, removably held in said pockets, whereby the absence of any card insert in the series from its pocket will be visually indicated by exposing to view the margin of the corresponding overlapped card in said pocket.

9. An index comprising a frame having inwardly facing guide channels, a series of 60 cards, means engaging said guide channels

for supporting said cards in overlapped spaced relation with their free margins projecting one beyond another, and a series of transparent sheaths on the free edges of the cards, each having a closed front face and rearwardly and inwardly bent lips one overlapping the other, the front lip forming with the closed front face a compartment adapted to receive an index slip and forming with the rear lip a pocket adapted to 70 receive a card insert, said overlapping card being permanently secured to the rear lip and extending into said pocket, index slips in said compartments shorter than said compartments to expose to view the interior of 75 said pockets through said transparent compartments at one or both ends of the index slips, and card inserts visually differentiated from said overlapped cards, removably held in said pockets, whereby the absence of any 80 card insert in the series from its pocket will be visually indicated by exposing to view the margin of the corresponding overlapped card in said pocket.

10. A card having a sheath of transparent resilient material at one edge forming a pocket, and a removable insert in said pocket, the front wall of said pocket being yieldingly urged toward the rear wall by the resilience of the material of the sheath, 90 whereby a spring grip will be exerted on the insert in said pocket.

11. A card having a sheath of transparent resilient material at one edge, said sheath comprising a closed front face, and rearwardly and inwardly bent lips overlapping each other, the front lip forming with the front face a compartment adapted to receive an index slip and forming with the rear lip a pocket adapted to receive a card 100 insert.

12. A card having a sheath of transparent resilient material at one edge, said sheath comprising a closed front face, and rearwardly and inwardly bent lips overlapping each other, the front lip forming with the front face a compartment adapted to receive an index slip and forming with the rear lip a pocket adapted to receive a card 110 insert, said card extending into said pocket 115 and secured to said rear lip.

13. A card having a sheath of transparent resilient material at one edge, said sheath comprising a closed front face, and rearwardly and inwardly bent lips overlapping each other, the front lip forming with the front face a compartment adapted to receive an index slip and forming with the rear lip a pocket adapted to receive a card 120 insert, said front lip being yieldingly urged toward said rear lip by the resilience of the material, whereby a spring grip will be exerted on the insert in said pocket.

14. A card having a sheath of transparent resilient material at one edge, said 130

4

sheath comprising a closed front face, and rearwardly and inwardly bent lips overlapping each other, the front lip forming with the front face a compartment adapted to receive an index slip and forming with the rear lip a pocket adapted to receive a card insert, said card extending into said pocket, an index slip in said compartment, and an insert in said pocket, said front lip being 10 yieldingly urged toward said rear lip by the resilience of the material, whereby a spring grip will be exerted on the insert in said pocket.

15. A sheath for an index device made of transparent resilient sheet material comprising a closed front face and rearwardly and upwardly bent lips, one overlapping the other, the forward lip forming with the rear lip a pocket, and forming with the front face a separate compartment adapted to receive an index slip.

16. A sheet for an index device made of transparent resilient sheet material comprising a closed front face and rearwardly and inwardly bent lips, one overlapping the other, the forward lip forming with the rear lip a pocket, and forming with the front face a separate compartment adapted to receive an index slip, said lips being yieldingly urged toward each other by the resilience of the material whereby said pocket constitutes a spring clip.

17. A sheath for an index device made of

transparent resilient sheet material, comprising a closed front face and rearwardly 35 bent lips, one overlapping the other, the free edge of the rear lip projecting beyond the edge of the front face, said lips being yieldingly urged toward each other by the resilience of the material whereby to exert 40 a spring grip on a card extending between them.

18. A card having a sheath of transparent resilient material at one edge, said sheath comprising a closed front face, and rearwardly and inwardly bent lips overlapping each other, the front lip forming with the front face a compartment adapted to receive an index slip and forming with the rear lip a pocket adapted to receive a card 50 insert, said front lip being yieldingly urged toward said rear lip by the resilience of the material, whereby a spring grip will be exerted on the insert in said pocket, an index 55 slip in said compartment, and an adjustable indicator member having a signal portion located between the front face of the sheath and the index slip, and a tab portion bent over one edge of the index slip and projecting outside of the sheath, between said resilient lips, and lying substantially flatwise 60 of the card.

Signed by me at North Tonawanda, New York, this 16th day of June 1916.

JAMES H. RAND.
